Primary Examiner — Mitchell Siegel

(74) Attorney, Agent, or Firm — Jerome J. Norris

(72) Inventor: **Randolph G. Clare, Jr.**, Washington, DC (US)

(57) **CLAIM**

The ornamental design for two-handed, finger indented golf training memory grip, as shown and described.

(**) Term: **14 Years**

DESCRIPTION

(21) Appl. No.: **29/463,877**

FIG. 1 is a perspective view of the two-handed, finger indented golf training memory grip;

(22) Filed: **Mar. 25, 2014**

FIG. 2 is a perspective view of the two-handed, finger indented golf training memory grip;

(51) **LOC (10) Cl.** 21-02

FIG. 3 is a right side view of the two-handed, finger indented

(52) **U.S. Cl.**

golf training memory grip;

USPC D21/758

FIG. 4 is a left side view of the two-handed, finger indented

(58) **Field of Classification Search**

golf training memory grip;

USPC D21/756-758; 473/300-303, 201-204

FIG. 5 is a front side view of the two-handed, finger indented
